UNITED STATES PATENT OFFICE.

GEORGE E. BARNHART, OF PASADENA, CALIFORNIA.

PONTOON FOR HYDROAEROPLANES AND PROCESS OF PRODUCING THE SAME.

Application filed November 23, 1926. Serial No. 150,923.

My invention relates to hydro-aeroplane pontoons and to a method of producing the same.

The objects of my invention are: First, to provide a pontoon for hydro-aeroplanes which is very rigid of construction so that the same will effectively withstand and resist all natural and unusual strains and impacts occasioned by striking the water head on when landing, at the side when skidding, and dropping directly into the water in case of a stall; second, to provide a pontoon of this class in which the weight of the craft above the pontoon and the force of the same against the pontoon is uniformly distributed, from without, by struts and braces, and by interior braces, to the bottom or hull portion of the pontoon; third, to provide a pontoon of this class in which the force of the craft above the pontoon is uniformly distributed to a center and side keelsons extending longitudinally within the pontoon, as well as to the chines or bilge keelsons at the extreme lateral sides of the pontoon; fourth, to provide a pontoon of this class in which the side-swipe of the craft is concentrated on the side keelsons and uniformly distributed over the pontoon; fifth, to provide a pontoon of this class having side keelsons at the opposite sides of the center keelson, which side keelsons, comprising structural framework, extend from the deck to the hull portion of the enclosing shell or covering; sixth, to provide a pontoon of this class having side keelsons of the class mentioned whereby the framework of the pontoon may be easily constructed and readily reinforced with other members of the pontoon so that the covering or shell at the outside of the pontoon may be secured to the framework without removing the same from the supporting means on which the pontoon is supported for constructing the same, or without removing any material portion of the supporting means to permit access to the framework from below; seventh, to provide a pontoon of such type as to be equally adapted to wood and metal construction; eighth, to provide as a whole a novelly constructed pontoon for hydro-aeroplanes; ninth, to provide a novel method for producing pontoons of this class; and, tenth, to provide a pontoon of this class which is simple and economical of construc-

tion and which will not readily deteriorate or yield to unusual forces.

With these and other objects in view, as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a side elevational view of my pontoon for hydro-aeroplanes; Fig. 2 is a plan view thereof showing the struts broken away and in section; Fig. 3 is a front elevational view thereof; Fig. 4 is a rear end elevational view; Fig. 5 is a top view thereof showing the upper shell portion or covering broken away and in section, and also the deck formers and deck ribs at one side of the pontoon broken away and in section to facilitate the illustration; Fig. 6 is a partial sectional and partial side elevational view thereof taken on the line 6—6 of Fig. 5; Fig. 7 is a longitudinal sectional view thereof taken on the line 7—7 of Fig. 5, showing certain parts and portions in elevation to facilitate the illustration; and Figs. 8, 9 and 10 are transverse sectional views thereof, taken respectively through 8—8, 9—9 and 10—10 of Fig. 5.

Like characters of reference refer to similar parts and portions throughout the several views of the drawings.

The essential parts and portions of my pontoon consist of the lower chines or bilge keelsons 1, deck chines 2, longitudinal keelson 3, side keelsons 4, transverse bulkheads 5, 6 and 7, deck formers 8, deck ribs 9, shell or deck and hull covering 10, step formers 11, step plate 12, step struts 13, craft supporting struts 14, 15 and 16, reinforcing members 17, diagonal braces 18 and 19, and the side-swipe sockets 20 and 21.

The chine 1, or sometimes called "bilge keelson", extends around the whole bottom portion of the pontoon and forms the lower outer edge or corner thereof. Said chine may be made of one piece and curved around the bow in a wide sweep, or the same may be made in separate pieces. The rear ends of the chine 1 are connected together in a relatively sharp fin end. Extending from bow

to stern, midway between the side portions of the chine, is the center or longitudinal keelson 3 which is secured at its forward and rear ends to the corresponding ends of the chines and extends preferably beyond the rear ends thereof. At the opposite sides of the center keelson between the same and the complete or continuous chine 1, are positioned other or side keelsons 4 which extend 10 fore and aft and are secured at their forward and rear ends to the chine 1 in spaced relation to the center keelson. The keelsons and the chine or chines are spaced laterally relative to each other by means of trans- 15 verse bulkheads 5, 6 and 7 which bulkheads divide the hull of the pontoon into four or any other number of watertight compartments. It will be noted that such bulkheads may not be watertight, if desired, but 20 may only serve as transverse reinforcing frames.

At the lower side and intermediate the ends of the chines (by chines being meant the portions of the continuous chine at the 25 opposite side of the pontoon), are provided the angularly shaped step forming members 11 which provide a frame work for the conventional step provided in hydro-aeroplane pontoons. Connecting said step forming 30 members at their rear ends and also the vertically offset lower frame members 3^a and 3^b of the center keelson, is the step plate 12 which is reinforced angularly relative to the upper portion of the bulkhead 6 on the center keelson by means of diagonal braces or 35 step struts 13. Extending diagonally backwardly, upwardly and inwardly from immediately behind the step formers are the deck chines 2, which chines extend backwardly 40 and are secured at their rear ends to the upper edge and rear end of the center keelson. It is noted that the rear end of the center keelson is preferably provided with a wide strut 3^c which forms the rear end of 45 the pontoon.

Extending longitudinally from the forward to the rear end of the framework, that is, from the forward to the rear portions of the chines, are the longitudinal deck formers 8 which are relatively small ribs. Extending transversely between and secured to the edges of the keelsons, chines and deck formers, are the deck ribs 9, which in the pontoon shown are curved for forming a 50 round deck for the pontoon. The superimposed chines 1 and the deck chines 2 are connected by vertical deck ribs and form the substantially straight sides which connect the rounded and wide fore portion with the 55 sharp fin end. The bottom of the framework is similarly provided with longitudinal and transverse formers and ribs. Over the outer portions of both the upper and lower sides of the several keelsons, chines, ribs, 60 formers, and the like, is secured a shell or

covering of any suitable nature, such as wood panels, metal plate, fabric, fiber, bakelite, or the like.

It will be noted that the bottom of the hull or shell to either side of the center keelson, 70 is inclined outwardly and upwardly both forwardly and to the rear of the step, as in conventional pontoon construction. It will be also noted that the forward portion of the bottom of the pontoon is curved upwardly in gradual curves and terminates in a substantially sharp edge at the forward portion of the rounded deck.

The center keelson, as well as the side keelsons, are made of rigid skeleton framework 80 and extend as continuous structures from their forward to their rear intersections with the shell and from the upper to the lower sides, or from the deck to the hull portions of the shell, thus forming a rigid structure. 85

The portion of the center keelson between the forward and rearmost transverse bulkheads 5 and 7, is preferably divided, and formed with a longitudinal bulkhead portion 3^d which may consist of panels or boards 90 extending diagonally from the upper longitudinal member of the keelson to the rear and downwardly, as shown in Fig. 7. The structural framework of the center keelson is preferably built on and at the opposite 95 sides of its bulkhead portion.

Secured to the center keelson and extending upwardly therefrom beyond the upper side of the pontoon, are struts 14, 15 and 16. Although three struts are shown, the number may vary according to requirements. Said struts are preferably bifurcated at their lower ends and straddle the center keelson at the bulkhead portion. The upper longitudinal members of the center keelson are 105 preferably reinforced at their opposite sides, at the portions traversed by the struts, by means of reinforcing members 17, said members reinforcing the upper member of the keelson by reason of weakening of the same 110 in securing the struts thereto. It will be noted that each of the struts are positioned contiguous to a transverse bulkhead and terminate at their lower ends at such bulkhead. The forward or landing strut 14, 115 which absorbs the greatest shock and strains when landing the hydro-aeroplane, is usually of larger dimensions and extends diagonally from the craft proper to the forward portion of the hull having the forwardly inclined bottom. In Figs. 5, 6 and 7 of the drawings, I have shown diagonal braces or tubes 18 and 19 which extend from the strut 14 immediately within the shell to the lower portion of the transverse bulkhead 5, and 120 also at the intersection therewith of the side keelsons and the chines. The maximum strain on the pontoon is distributed from the strut 14 mainly to the center keelson and side keelsons; considerable of such strain, 125

130

however, is also distributed to the chines, the forward transverse bulkhead, the longitudinal deck and hull formers, as well as to the shell, and, therefore, substantially uniformly, 5 over the whole of the framework and shell of the pontoon.

To the shell of the pontoon, directly over the side keelsons and at the intersections therewith of the forward and rear transverse 10 bulkheads, are secured sockets 20 and 21, as shown in Figs. 1, 2 and 6, to which are secured the usual diagonal braces extending from the wings or other portions of the craft to take up the side swipe due to skidding, 15 waves, or other conditions.

The sockets 20 and 21, it will be noted, positioned as stated, also uniformly distribute the lateral force due to side swipe of the craft, over the whole or substantially the 20 whole of the pontoon.

In the construction of pontoons for hydro-aeroplanes, it has been customary to use low side keelsons in the bottom of the pontoon, at the opposite side of the longitudinal axis, 25 necessitating elaborate exterior construction framework for supporting the interior framework of the pontoon in position while securing the upper shell portion in position thereto, and then turning the pontoon up side 30 down for securing the hull portion of the shell to the interior framework. With my construction of the interior framework of the pontoon, the same is rigid and self-supporting and requires only a very limited exterior supporting frame structure. Therefore, the hull or bottom portion of the shell 35 may be secured in place without removing the pontoon as a whole from the supporting means or exterior supporting framework, 40 thus reducing to a minimum the necessity of such exterior supporting frame structure and greatly facilitating the construction of the pontoon. Such structure also reduces the number and accuracy of jigs and forms in the 45 construction of the pontoon, and further allows a greater number of men to work with ease around a single pontoon.

The process of constructing the pontoon is briefly as follows:

50 The center and side keelsons are fitted and assembled on flat assembling tables which serve as jigs and supporting means. The struts are fitted to the center keelson on another flat table suitable therefor. The 55 chines, including the deck chines, are bent to shape in an external mold, or supporting structure. The center keelson, together with the struts and step plate or step forming member, is positioned in the supporting 60 structure, located relative to the formed chines and secured at its ends thereto. The side keelsons are then located relative to the chines at the opposite sides of the center keelson and secured at its ends to the 65 former. The transverse bulkheads and

diagonal side braces are then fitted and secured in position. Then the longitudinal deck braces, the transversely curved deck ribs, the bottom or floor ribs, and the bottom of the shell are then put on in the 70 order named. The deck or upper portion of the shell may be put on while the pontoon is in the mold, or after being removed therefrom.

It will be here noted that though I have 75 confined my description and illustrations to pontoons, and particularly to pontoons for hydro-aeroplanes, my invention is applicable to other similar bodies, shells, or hulls, and the reference to pontoons is intended to include the former.

Though I have shown and described a particular construction, combination and arrangement of parts and portions of my pontoon, and a particular method of producing the same, I do not wish to be limited to this particular construction, combination and arrangement, nor to the particular method, but desire to include in the 85 scope of my invention, the construction, combination and arrangement substantially as set forth in the appended claims.

Having thus described my invention, what I claim as new and desire to secure by Letters Patent is:

1. In a pontoon of the class described, chines forming the lateral contour of the pontoon, a center keelson extending from end to end of the pontoon intermediate the 100 chines, side keelsons, one positioned at either side of and spaced from said center keelson, and a covering enclosing said chines and keelsons, said side keelsons extending from deck to hull portion of said covering and to said covering at the forward and aft 105 ends of the side keelsons.

2. In a pontoon of the class described, chines forming the lateral contour of the pontoon, a center keelson extending from end to end of the pontoon intermediate the 110 chines, side keelsons, one positioned at either side of and spaced from said center keelson, a covering enclosing said chines and keelsons, struts extending upwardly from the axial portion of the pontoon and secured to said center keelson, and angular braces extending from one of said struts to said side keelsons adjacent the hull.

3. In a pontoon of the class described, chines forming the lateral contour of the pontoon, a center keelson extending from end to end of the pontoon intermediate the 120 chines, side keelsons, one positioned at either side of and spaced from said center keelson, a covering enclosing said chines and keelsons, said side keelsons extending from deck to hull portion of said covering and to said covering at the forward and aft ends of the side keelsons, struts extending upwardly from said covering at the axial portion of 125

the pontoon and secured to said center keelsons within the covering, and angular braces within said covering and extending from one of said struts to said side keelsons adjacent the hull.

4. In a pontoon of the class described, chines forming the lateral contour of the pontoon, a center keelson extending from end to end of the pontoon intermediate the chines, side keelsons, one positioned at either side of and spaced from said center keelson, a covering enclosing said chines and keelsons, struts extending upwardly from the axial portion of the pontoon and secured to said center keelson, and angular braces extending from one of said struts to said chines.

5. In a pontoon of the class described, chines forming the lateral contour of the pontoon, a center keelson extending from end to end of the pontoon intermediate the chines, side keelsons, one positioned at either side of and spaced from said center keelson, a covering enclosing said chines and keelsons, said side keelsons extending from deck to hull portion of said covering and to said covering at the forward and aft ends of the side keelsons, struts extending upwardly from said covering at the axial portion of the pontoon and secured to said center keelson within said covering, angular braces extending from one of said struts to said side keelsons adjacent the hull, and other angular braces extending from said one strut angularly, forwardly and to the side toward said chines adjacent the hull.

6. In a pontoon of the class described, a framework including chines, a covering for said framework, struts extending upwardly from the pontoon and secured to said framework, and angular rod braces extending from one of said struts to the chines at the opposite sides of the pontoon.

7. In a pontoon of the class described, a framework including chines, a covering for said framework, struts extending upwardly from the pontoon and secured to said framework, and angular rod braces positioned within the covering and extending from one of said struts within said covering angularly, forwardly and to the side toward the chines at the opposite sides of the pontoon.

8. In a pontoon of the class described, a framework including side keelsons positioned at the opposite sides of the longitudinal axis of said framework and intersecting with the forward and aft portions thereof, a covering for said framework and said side keelsons, a strut secured to said framework and extending upwardly from said covering, and braces extending from said strut to said side keelsons.

9. In a pontoon of the class described, a framework including side keelsons positioned at the opposite sides of the longitudinal axis of said framework and intersecting with the forward and aft portions thereof, a covering for said framework and said side keelsons, a strut secured to said framework and extending upwardly from the axial portion thereof, and angular braces extending from said strut forwardly to the side toward said side keelsons adjacent the hull portion of the covering.

10. In a pontoon of the class described, a framework including a center keelson extending from end to end at the longitudinal axis of said framework, side keelsons positioned at the opposite sides of said center keelson and intersecting with the forward and aft portions of said framework, all of said keelsons consisting of structural frames extending the full height of the framework.

11. In a pontoon of the class described, a framework including a center keelson extending from end to end at the longitudinal axis of said framework, side keelsons positioned at the opposite sides of said center keelson and intersecting with the forward and aft portions of said framework, all of said keelsons consisting of structural frames extending the full height of the framework, a covering for said framework and a plurality of transverse bulkheads extending from side to side and from deck to hull portion of said covering, said transverse bulkheads dividing the interior of said pontoon into separate compartments.

12. In a pontoon of the class described, a framework including a center keelson extending from end to end at the longitudinal axis of said framework, side keelsons positioned at the opposite sides of said center keelson and intersecting with the forward and aft portions of said framework, all of said keelsons consisting of structural frames extending the full height of the framework, a covering for said framework and a plurality of transverse bulkheads extending from side to side and from deck to hull portion of said covering, said center keelson between the forward and aft transverse bulkheads being in the form of a solid wall and serving as a dividing longitudinal bulkhead.

13. In a pontoon of the class described, a framework including a center keelson extending from end to end at the longitudinal axis of said framework, side keelsons positioned at the opposite sides of said center keelson and intersecting with the forward and aft portions of said framework, all of said keelsons consisting of structural frames extending the full height of the framework, a covering for said framework, a plurality of transverse bulkheads extending from side to side and from deck to hull portion of said covering, a plurality of struts secured to said center keelson and extending above the

covering of the pontoon, the forward strut being positioned at an angle forwardly and downwardly and extending to the intersection of one of the transverse bulkheads with 5 said center keelson at the hull portion of the covering.

14. In a pontoon of the class described, a framework including a center keelson extending from end to end at the longitudinal 10 axis of said framework, side keelsons positioned at the opposite sides of said center keelson and intersecting with the forward and aft portions of said framework, all of said keelsons consisting of structural frames 15 extending the full height of the framework, a covering for said framework, a plurality of transverse bulkheads extending from side to side and from deck to hull portion of said covering, and a plurality of struts secured 20 to said center keelson at the portions thereof intersected by said transverse bulkheads and extending upwardly therefrom beyond said covering.

15. In a pontoon of the class described, 25 a framework including a center keelson and side keelsons extending to the forward and aft portions of said framework, all of said keelsons consisting of structural frames extending the full height of the framework, 30 a covering for said framework, a plurality of transverse bulkheads extending from side to side and from deck to hull portion of said covering, a plurality of struts secured to said center keelson and extending above 35 the covering of the pontoon, the forward strut being positioned at an angle forwardly and downwardly and extending to the intersection of one of the transverse bulkheads with said center keelson at the hull 40 portion of the covering, and a plurality of angular braces extending from said struts, at the portion thereof immediately within said covering, to said side keelsons and the outer portions of said framework adjacent 45 the hull portion of said covering.

16. In a pontoon of the class described, 50 a framework including a center keelson and side keelsons extending to the forward and aft portions of said framework, all of said keelsons consisting of structural frames extending the full height of the framework, 55 a covering for said framework, a plurality of transverse bulkheads extending from side to side and from deck to hull portion of said covering, said transverse bulkheads dividing the interior of said pontoon into 60 separate compartments, said center keelson between the forward and aft transverse bulkheads being in the form of a solid wall 65 and serving as a dividing longitudinal bulkhead, and a plurality of struts straddling said center keelson at the bulkhead portion thereof and serving to reinforce the same, said struts extending outwardly beyond and above the covering of the pontoon, the for-

ward struts being positioned at an angle downwardly and forwardly and terminating at the portion of the center keelson adjacent one of said transverse bulkheads and to the hull portion of the covering. 70

17. In a pontoon of the class described, a framework including a center keelson and side keelsons extending to the forward and aft portions of said framework, all of said keelsons consisting of structural frames extending the full height of the framework, a covering for said framework, a plurality of transverse bulkheads extending from side to side and from deck to hull portion of said covering, said transverse bulkheads dividing the interior of said pontoon into separate compartments, said center keelson between the forward and aft transverse bulkheads being in the form of a solid wall and serving as a dividing longitudinal bulkhead, a plurality of struts straddling said center keelson at the bulkhead portion thereof and serving to reinforce the same, said struts extending outwardly beyond and above the covering of the pontoon, the forward struts being positioned at an angle downwardly and forwardly and terminating at the portion of the center keelson adjacent one of said transverse bulkheads and the hull portion of the covering, and a plurality of braces 90 extending from said forward struts, immediately within said covering, forwardly, downwardly and to the sides to said side keelsons and to the extreme side portions 95 of said framework. 100

18. In a pontoon of the class described, chines forming the sides of the pontoon, a center keelson extending from end to end of the pontoon intermediate the chines, side keelsons, one positioned at either side of and spaced from said center keelson, a covering enclosing said chines and keelsons, said side keelsons extending from deck to hull of said covering and to said covering at the forward and aft ends of the side keelsons, and means at the outer upper sides of said covering for securing side-swipe braces, said means being in alignment with said side keelsons. 105 110

19. In a pontoon of the class described, a framework including a center keelson extending from end to end at the longitudinal axis of said framework, side keelsons positioned at the opposite sides of said center keelson and intersecting with the forward and aft portions of said framework, all of said keelsons consisting of structural frames extending the full height of the framework, a covering for said framework, a plurality of transverse bulkheads extending from side to side and from deck to hull portion of said covering, said transverse bulkheads dividing the interior of said pontoon into separate compartments, and means at the outer upper sides of said covering for securing 115 120 125 130

side-swipe braces, said means being in alignment with said side keelsons, and with certain of said transverse bulkheads.

20. The herein described process of producing pontoons for hydro-aeroplanes consisting in forming a chine of the desired lateral contour of the pontoon and clamping the same in place in a supporting means, then mounting center and side keelsons on the supporting means and securing the same at their ends to said chines and reinforcing the same relative to each other, and then securing the covering over said chines and keelsons without removing the same from said supporting means.

21. The herein described process of producing pontoons for hydro-aeroplanes consisting in forming a chine of the desired lateral contour of the pontoon and clamping the same in place on a supporting means, then mounting center and side keelsons, having supporting struts, on the supporting means and securing the same at their ends to said chines, then securing auxiliary longitudinal and transverse reinforcing framework on and between said keelsons and chines, and then securing a shell to the outer sides of said keelsons, chines and framework.

22. The herein described process of producing pontoons for hydro-aeroplanes consisting in forming a chine of the desired lateral contour of the pontoon and clamping the same in place on a supporting means, then mounting center and side keelsons, having supporting struts, on the supporting means and securing the same at their ends to said chines, then securing auxiliary longitudinal and transverse reinforcing framework on and between said keelsons and chines, and then securing a shell to the outer sides of said keelsons, chines and framework.

23. The herein described process of producing pontoons for hydro-aeroplanes consisting in forming a chine of the desired lateral contour of the pontoon and clamping the same in place on a supporting means, then mounting center and side keelsons on the supporting means and securing the same at their ends to said chines and reinforcing the same relative to each other, and then securing an outer covering to the bottom sides of said chines and keelsons while the same are supported on said supporting means.

In testimony whereof, I have hereunto set my hand at Pasadena, California, this 4th day of November, 1926.

GEORGE E. BARNHART.
